INVENTOR
FRANK G. DELBON
BY
John C. Giel
ATTORNEY

UNITED STATES PATENT OFFICE.

FRANK G. DELBON, OF BROOKLYN, NEW YORK.

SHANK STIFFENER.

Application filed November 16, 1921. Serial No. 515,476.

To all whom it may concern:

Be it known that I, FRANK G. DELBON, a citizen of the United States, and resident of Brooklyn, in the county of Kings and State 5 of New York, have invented certain new and useful Improvements in Shank Stiffeners, of which the following is a specification.

The invention relates to shank-stiffeners for shoes, boots and the like, and it consists 10 in a shank-stiffener of the novel construction hereinafter described and claimed.

The shank-stiffener of the present application embodies certain improvements on the shank-stiffeners described in Letters Patent 15 granted to me December 24, 1907, and numbered, respectively, 874,396 and 874,884.

The shank-stiffener made the subject of this application possesses all the advantages 20 of the shank-stiffeners disclosed in the aforesaid Letters Patent, and in addition certain further advantages in that my new shank-stiffener affords increased comfort to the wearer and is better adapted to the last on which the shoe is made, thereby facilitating 25 the manufacture of shoes.

The shank-stiffener is formed from one integral piece of sheet steel and is of special outline and construction adapting the stiffener to efficiently support the plantar arch 30 of the foot in a manner affording great comfort to the wearer and to yield to irregularity of pressures which may be brought against it. The body portion of my shank-stiffener has been specially designed to meet 35 the requirements of the anatomical structure of the human foot and with due regard to the pressures brought against the tarsal and metatarsal bones of the foot during walking, and to these ends I form the body portion of 40 my shank-stiffener with three longitudinal sections slit therein and disposed to form a lower substantially central longitudinally ribbed section merging at its ends into the end portions of the shank-stiffener and two 45 opposite side sections displaced inwardly to overlap said central section and therewith afford a concave seat for the ligaments of the foot thereat, said three sections also constituting a novel yielding support for the arch 50 of the foot and providing at the lower side of the shank-stiffener a proper longitudinal ridge for producing a desirable finish in the shank portion of a shoe.

The invention will be fully understood 55 from the detailed description hereinafter

presented, reference being had to the accompanying drawings, in which:

Fig. 1 is a plan view of a metal blank which I first form in manufacturing my shank-stiffeners and from which the shank-stiffener, without further cutting of the metal, is produced by means of suitable forming dies;

Fig. 2 is a bottom plan view of the shank-stiffener of my invention;

Fig. 3 is a top plan view of the same;

Fig. 4 is a side view of the same, and

Fig. 5 is a cross-section of the same on the dotted line 5—5 of Fig. 3.

In the drawings, 10 designates the shank-stiffener as a whole, and this stiffener, as shown in Fig. 4, arches upwardly and rearwardly from the forward end 11 toward the heel end 12 thereof to conform to the shape desired for the arch or shank portion of a 75 shoe. In length the shank-stiffener will extend from above the heel to the rear end of the tread of the sole of the shoe.

At its heel-end the shank-stiffener has rearwardly converging side edges, and along 80 its middle portion the shank-stiffener has inwardly curved side edges 13, while at its forward end the shank-stiffener has the very beneficial formation described in my aforesaid Letters-Patent, to wit: the table section 85 14 of approximately triangular outline defined at its inner edges at the bend-lines 15 diverging from a point 16, which represents the forward end of the shank portion of the shank-stiffener and is formed at the forward 90 terminal of a downwardly projecting rib 17 which extends lengthwise of the shank-stiffener and is formed by pressing the metal downwardly to produce said rib or ridge 17.

The shank-stiffeners are made in rights 95 and lefts for pairs of shoes, Fig. 3 showing a shank-stiffener for a left shoe, and Fig. 2 in outline showing the edge outline of a shank-stiffener for a right shoe.

One of the main features of my present 100 invention resides in the novel construction of the shank or body portion of the shank-stiffener, and this portion comprises a central longitudinal section 18 and two side longitudinal sections 19, which, intermediate their ends, curve inwardly toward each other and over upon the middle section 19, as shown in Fig. 3.

The sections 18, 19 are primarily formed 110 by slitting the metal blank shown in Fig. 1,

longitudinally at 20, 20 to form three substantially co-equal divisions, the middle one for the section 19 and the two side ones for the sections 18.

5 The slits 20 start slightly to the rear of the forward table 14 and finish at the upper end of the forwardly arched portion of the stiffener, as shown.

By means of a combination die and forming 10 machine, the blank has the table 14 formed at its forward end and its side portions at each side of its longitudinal center bent downwardly into somewhat V-outline in cross-section to form the ridge 17 and generally 15 shape the stiffener rearwardly of the table 14, and on this same machine the middle section 18 is then bent downwardly and the side sections 18 are crowded edgewise inwardly toward each other and over the then 20 depressed section 18 to such extent as may be desired, after which the section 18 is moved up against the sections 19 and the finishing of the arching and details of the shank-stiffener is performed.

25 The middle section 18 in the finished article, between the slits 20, is approximately in cross-section in the outline of a shallow V, as shown in Fig. 5, and the side sections 19 lap upon the section 18 but extend outwardly beyond the same and gradually curve inwardly and downwardly against the upper side portions of said section 18 thereby forming a shallow longitudinal seat, at 21, for the plantar ligaments of the foot. The upper 30 outer portions of the sections 19 are almost flat so as to avoid abruptness in the seat 21 and to adapt the structure to the inner shoe-sole and to the last. The inner side portions of the sections 19, bylapping upon the middle section 18, avoid what would otherwise 35 be a deep and abrupt longitudinal depression in the body of the shank-stiffener and provide a proper seat or bearing for the last and, in the shoe, for the arch of the 40 foot.

The sections 18, 19 arranged as shown also provide a support which permits a downwardly yielding of the stiffener entirely across the same when necessary, and at the 50 same time allows either side section to yield downwardly, backed by the section 18, in accordance with the direction of the pressure exerted and the anatomical construction of the foot or the habit of the wearer in 55 walking.

The sections 19 due to their displacement inwardly over the section 18, become curved at their opposite edges, their outer edges becoming concavely curved, as at 13, and 60 their inner edges convexly curved as shown by full lines in Fig. 3, and by dotted lines in Fig. 2.

The shank-stiffener constructed as hereinbefore described affords special advantages in support for the arch portion of a foot

and is adapted to situations to be met in the condition of the foot, whether normal or weakened, and in the walking habits of the wearers of the shoes.

What I claim as my invention and desire to secure by Letters Patent, is:

1. A shoe shank-stiffener of the character described having at its forward end a broadened section adapted to the rear end of the tread portion of a shoe and in its body portion downwardly converging sides, said body-portion having a middle longitudinal section and side sections displaced inwardly toward each other beyond the outer side edges of said middle section, the whole being in one integral piece of sheet metal slit to provide said middle and side sections. 75

2. A shoe shank-stiffener of the character described having at its forward end a broadened section adapted to the rear end of the tread portion of a shoe and in its body portion downwardly converging sides, said body-portion having a middle longitudinal section affording at its bottom a longitudinal downwardly projecting ridge and side sections displaced inwardly toward each other and overlapping the outer side edges of said middle section and therewith forming a shallow longitudinal recess, the whole being in one integral piece of sheet metal slit to provide said middle and side sections. 90 95

3. A shoe shank-stiffener of the character described having at its forward end a broadened section adapted to the rear end of the tread portion of a shoe and in its body portion downwardly converging sides, said body portion having a middle longitudinal section and side sections which curve inwardly toward each other beyond the outer side edges of said middle section, said side sections being concavely curved at their outer edges and convexly curved at their inner facing side edges, and the whole being in one integral piece of sheet metal slit to provide said middle and side sections. 100 105 110

4. A shoe shank-stiffener of the character described having at its forward end a laterally extending table portion defined at its inner edges by diverging angular lines denoting the forward end of the body of the shank-stiffener and in its body portion downwardly converging sides and a longitudinal downwardly projecting ridge extending from the vertex of said angular lines to the heel portion of said body, said body portion having a middle longitudinal section and side sections displaced inwardly toward each other beyond the outer side edges of said middle section, the whole being in one integral piece of sheet metal slit to provide 115 120 125 said middle and side sections.

Signed at New York city, in the county of New York and State of New York, this 14th day of November, A. D. 1921.

FRANK G. DELBON.
